Primary Examiner — Cynthia R Underwood(57) **CLAIM**

The ornamental design for a “serving plate”, as shown and described.

DESCRIPTION

FIG. 1 is a top perspective view of the serving plate employing my new design;

FIG. 2 is a top view of FIG. 1;

FIG. 3 is a bottom view of FIG. 1;

FIG. 4 is a front end view of FIG. 1;

FIG. 5 is a rear end view of FIG. 1;

FIG. 6 is a right end view of FIG. 1;

FIG. 7 is a left end view of FIG. 1;

FIG. 8 is a cross-sectional view of FIG. 4 taken along line 8-8;

FIG. 9 is a cross-sectional view of FIG. 6 taken along line 9-9;

FIG. 10 is a top view of the serving plate of FIG. 1 in a partially collapsed position; and,

FIG. 11 is a top view of the serving plate of FIG. 1 in a fully collapsed position.

1 Claim, 8 Drawing Sheets(56)
